MICROWAVE HEATING APPARATUS
Louis H. Schall, Dedham, Mass., assignor to Raytheon
Company, Lexington, Mass., a corporation of Delaware

Filed Sept. 14, 1960, Ser. No. 55,960
3 Claims. (Cl. 219—10.55)

This invention relates generally to heating devices and more particularly to apparatus utilizing high frequency energy for the heating of materials.

In order to provide uniform and rapid heating of materials, high frequency energy, generally in the microwave region, may be utilized. The materials to be heated, which may be foodstuffs, or other industrial materials, are placed in an enclosure which is sealed to prevent the escape of the high frequency energy. The energy, which is generated by a known high frequency energy source, such as a magnetron, is inserted either directly into the enclosure or indirectly through the use of wave guides or other suitable devices.

In order to provide the most efficient heating of the material, the energy is directed toward the material from a location above the material. For this reason the magnetron is generally located at the top of the enclosure. It is advantageous that the power supplies and other electrical or mechanical equipment utilized in the apparatus be located below the enclosure, or oven cavity. In conventional configurations wherein the magnetron is placed at the top of the oven and the power supplies located below the enclosure, extensive cabling and relatively complicated construction design is required in order to transmit energy from the power supply to the magnetron and thence into the oven. Alternatively, the magnetron may be placed below the oven cavity and the energy inserted through the bottom of the oven enclosure in order to avoid these construction difficulties. However, such a bottom-feed device prevents the uniform heating of the material since, as mentioned above, it has been found that the best heating is obtained when the energy is coupled into the oven at a point above the load to be heated. In addition, for conventional bottom-feed construction, the magnetron must be protected from damage due to vapors or spillage of liquids that are being heated and, hence, extensive waterproofing of the bottom section is required.

This invention combines the advantages of coupling the high frequency energy into the enclosure at a region located above the load to be heated and the advantages of locating the microwave energy source at a position below the enclosure, without the normal disadvantages that usually accompany each. In one particular embodiment of the invention, the enclosure comprises a first main cavity region wherein the material to be heated is placed and a second coupling cavity located substantially at the rear of the enclosure. The microwave energy is inserted through the bottom wall of the enclosure into the rear coupling cavity. The coupling cavity is separated from the main cavity region by a partition which may be fabricated partially from a metallic material and partially from a dielectric material. The metallic portion of the partition is located substantially adjacent the energy source to prevent the energy from the source from immediately being directed toward and, thereby, overcoupling the load. The dielectric portion is located generally at a region above the material to be heated. The rear cavity has reflective surfaces that cause the energy to be deflected in a general upward direction where it is ultimately coupled from the rear cavity through the dielectric portion of the partition and, thence, downward over the load to be heated. A suitable stirring device may be located in the

2

coupling cavity so that the energy is uniformly distributed throughout the main oven area. Such a configuration assures a uniform distribution of energy throughout the load.

The invention may be more easily described with the help of the accompanying drawings in which:

FIG. 1 shows a sectional, elevation view of one embodiment of the invention;

FIG. 2 shows a top sectional view of the embodiment of the invention shown in FIG. 1 taken along the line 2—2;

FIG. 3 shows a sectional, elevation view of a second embodiment of the invention; and

FIG. 4 shows a top sectional view of the embodiment of the invention shown in FIG. 3 taken along the line 4—4.

In the apparatus shown in FIGS. 1 and 2 there is disclosed a microwave heating apparatus 10 having a bottom section 11 and an upper section 12. Bottom section 11 houses power supplies, cooling devices, and other electrical or mechanical equipment that may be required for operation. Upper section 12 comprises a metallic enclosure into a portion of which the material to be heated is placed. The upper section 12 comprises a first oven cavity 15 and a second coupling cavity 14 separated by 25 a partition 16 having a metallic portion 17 and a dielectric portion 18. Dielectric portion 18 is held at one end by a first bracket 30 attached to the upper end of metallic portion 17 and at the other end by a second bracket 31 attached at the front wall of upper section 12. At 30 the front of upper section 12 there is shown a door 13 slidably mounted to provide an access opening for placing a material 19 to be heated in oven cavity 15 as shown. Material 19 is placed on a suitable dielectric platform 20 held within cavity 15 by mounting brackets 21. The door 35 is arranged so that when it is closed it provides an adequate seal to prevent the escape of high frequency energy.

40 A microwave energy generator, such as a magnetron 22, is mounted at the bottom wall 23 of coupling cavity 14, the latter cavity being located in this embodiment at the rear of enclosure 12. The magnetron may, for example, have a dome-shaped portion 24 which functions as an electromagnetic radiator of energy conducted thereto from the magnetron cavity resonator. Such magnetrons, as 45 well as other types of magnetrons which are also adaptable for use with apparatus 10, are well known in the art, and, therefore, are not described in detail here. Other means, such as a waveguide, for coupling energy through the bottom wall into the enclosure, may also be used.

50 Coupling cavity 14, into which the energy is inserted, has a corner reflecting surface 26, placed substantially in the path of the energy from source 22. Thus, the energy is directed generally into the upper region 28 of enclosure 10. A mode stirring device 27 operated by a motor (not shown) is mounted at the top wall of enclosure 10. Thus, the energy which enters from microwave generating source 22 is coupled through the dielectric portion 18 of partition 16 downward toward the material 19 which is to be heated. The dielectric portion 18 provides a means for preventing cooking greases and vapors from entering coupling cavity 14 and spattering stirrer 27, magnetron 22 and the reflecting walls of cavity 14. It is within the scope of the invention to remove the dielectric portion 18 if cooking greases and vapors are not expected to be a source of difficulty.

55 Coupling cavity 14 has dimensions which are relatively greater than the wave length of the high frequency energy source 22. The basic excitation for the entering energy is the $TM_{1,1}$ mode but, because of the relatively large cavity size, substantially all modes are propagated within coupling cavity 14. The structure of the inven-

tion allows optimum coupling and stirring characteristics to be obtained. These characteristics may be determined by the stirrer position and the height of metallic portion 17 of partition 16, the latter dimension being shown as the distance X in the figure. By empirically adjusting dimension X and the stirrer position, a satisfactory impedance match and energy pattern can be obtained for a load placed within the main oven heating cavity 15.

A second embodiment of the invention is shown in FIGS. 3 and 4 wherein a microwave heating apparatus includes an oven enclosure 35 having a door 36, said enclosure resting on a structure 37 housing electrical and mechanical equipment including a power supply for a magnetron energy source 38 mounted at the bottom wall 39 at the rear of oven enclosure 35. The dome-shaped radiator 40 of magnetron 38 is inserted into a coupling cavity 41 formed by a first slanted partition 42 on one side, the slanted rear wall 43 of enclosure 35, and portions of the side, top and bottom walls of the enclosure. Partition 42 comprises a metallic portion 44 having an opening 45 therein. Opening 45 is covered by a dielectric piece 46 and a mode stirrer 47 is mounted at the rear wall 43 within coupling cavity 41. A load 48 to be heated is placed within main oven heating cavity 49. Material 48 may be mounted on a dielectric platform 50 held by suitable brackets 51. For clarity the blades of mode stirrer 47 are not shown in FIG. 4.

The configuration shown in FIGS. 3 and 4 thereby directs the energy from source 38 to load 48 through opening 45 so that the energy which is inserted at the bottom wall 39 of enclosure 35 is transmitted to the load from a point above the load to be heated. Thus, the configuration of FIGS. 3 and 4 provides the advantages of bottom-feed with the advantages of coupling the bottom-fed energy to the load from a region above the load.

It is clear that other embodiments of the invention will occur to those skilled in the art that are within the scope of this invention. For example, the invention need not be limited to the use of a single energy source inasmuch as a plurality of magnetrons, or other high frequency sources, may be used to provide energy to the coupling cavity for transmittal to the main oven cavity. Moreover, the coupling cavity need not be located at the rear of the enclosure but may extend along the side walls, for example. Other suitable variations in the basic structure of the invention may be devised by those in the art and, hence, the invention is not to be limited to the particular embodiment disclosed herein except as defined by the appended claims.

What is claimed is:

1. A microwave heating apparatus comprising an enclosure having at least a bottom wall and having a material-receiving cavity therein, an energy coupling cavity in the enclosure extending at one side and above the material-receiving cavity, a partition separating said cavities, means for generating and radiating microwave en-

ergy through the bottom wall of said enclosure into said energy coupling cavity, said partition having a dielectric portion located above said material-receiving cavity to provide a transmission path for said microwave energy from said energy coupling cavity into said material-receiving cavity whereby microwave energy is directed at material in said material-receiving cavity from a location above said material.

2. A microwave heating apparatus comprising: substantially rectangular shaped enclosure having a bottom wall, a top wall and a front, back and two side walls, an L-shaped partition extending from said front wall to said bottom wall and defining a material-receiving cavity and an energy coupling cavity, an access door on said front wall to provide access to said material-receiving cavity, means for generating and radiating microwave energy through the bottom wall of said enclosure into said energy coupling cavity, said L-shaped partition having a dielectric portion located parallel to said bottom wall to provide a transmission path for said microwave energy from said coupling cavity into said material-receiving cavity from a location above said material-receiving cavity, and stirrer means disposed in said energy coupling cavity directly above said dielectric portion for circulating said microwave energy in said energy coupling cavity down through said dielectric portion.

3. A microwave heating apparatus comprising: a substantially rectangular shaped enclosure having a bottom wall, a top wall and a front, back and two side walls, an L-shaped partition extending from said front wall to said bottom wall and defining a material-receiving cavity and an energy coupling cavity, an access door on said front wall to provide access to said material-receiving cavity, means for generating and radiating microwave energy through the bottom wall of said enclosure into said energy coupling cavity, said L-shaped partition having a dielectric portion located parallel to said bottom wall to provide a transmission path for said microwave energy from said coupling cavity into said material-receiving cavity from a location above said material-receiving cavity, and stirrer means disposed in said energy coupling cavity directly above said dielectric portion for circulating said microwave energy in said energy coupling cavity down through said dielectric portion.
